LEO IMBLUM, OF LA JUNTA, COLORADO.

COMBINED MANUAL AND POWER CONTROLLING MECHANISM.

1,258,337.

Specification of Letters Patent. Patented Mar. 5, 1918.

Application filed June 21, 1916. Serial No. 104,948.

To all whom it may concern:

Be it known that I, LEO IMBLUM, a citizen of the United States, and a resident of La Junta, in the county of Otero and State of Colorado, have invented a certain new and useful Improvement in Combined Manual and Power Controlling Mechanism, of which the following is a specification.

My present invention relates generally to controlling mechanisms for reversing gears, steering gear shifts, and other parts to be controlled of this general nature, and particularly to a compact and effective arrangement of parts whereby to permit of manual control in case the power actuated controlling parts are disabled or the source of power fails.

In the accompanying drawings illustrating my invention, and forming a part of this specification.

Figure 1 is a side elevation illustrating the practical application of my invention, in connection with a locomotive reversing shaft.

Fig. 2 is a detail sectional view illustrating the locking device for the manual controlling rods.

Fig. 3 is an enlarged view, partly in section, of the power cylinder and its parts, together with the power controlling member.

Fig. 4 is a sectional view in detail through the power controlling member, and

Fig. 5 is a cross section through the power cylinder, taken substantially on line 5—5 of Fig. 3.

Referring now to these figures, and particularly to Fig. 1, I have shown for purposes of illustration, my invention in connection with a locomotive, the boiler of which appears at 10 and the reversing shaft of which appears at 11, with the bell crank 12 secured thereto, one arm of which is pivotally connected to the link hanger 13 and the other arm of which is connected to a reach rod 14.

My improvements propose the provision of a movable controlling member 15 to which the opposite end of the reach rod 14 is connected, said controlling member being bodily movable upon a guide rod 16 upon which it has bearing at 17, the upper portion of the said controlling member being provided with a transverse slot 18 dividing the same into forward and rear portions

19 and 20, these portions having axially aligned bores 21 and 22, the inner adjacent ends of which communicate with the atmosphere through the slot 18.

By reference particularly to Fig. 4, it will be noted that the outer end of the bore 21 is closed by a plug 23, and the outer end of the bore 22 receives one threaded end of a nipple 24, the opposite end of which is adapted for the reception of a flexible hose 65 or other connection 25 extending from a suitable source of pressure, as, for instance, the main air reservoir 26, as shown in Fig. 1.

Surrounding and communicating with the bores 21 and 22, are annular grooves 27 and 28 respectively communicating with depending ports 29 and 30, port 29 communicating at its opposite end with a pressure conveying tube 31, and port 30 communicating at its lower end with the outer ends of a tubular piston 32, through which the tube 31 extends in spaced co-axial relation.

Extending respectively into the bores 21 and 22 and forming pressure chambers therein, are the heads 33 and 34 of a piston 80 valve, the stem connecting which heads, is extended through the slot 18 between the side portions 19 and 20, and is pivotally connected at an intermediate point 35 with one depending angular end 36 of a manual controlling and actuating rod 37, the heads 33 and 34, as particularly seen in Fig. 4, being spaced apart to normally cover the grooves 27 and 28. The spaces within the bores 21 and 22 beyond the heads 33 and 34, are connected by pressure channels 38. These spaces are thus in communication at all times with the source of pressure through the nipple 24 which opens into one of the spaces, namely, the outer portion of the bore 22, as 95 before stated.

The piston rod 32 extends, with its internal tube 31, through one end of a power cylinder 39, and into connection with a piston 40 mounted for movement in opposite 100 directions within said cylinder, the respective end of the inner tube 31 communicating with an axial port 41 through the piston 40 and thus, with the cylinder space 42, at one side of the piston 40, and the rod 32 having 105 laterally projecting ports 43 as clearly seen in Figs. 3 and 5, opening into the cylinder space 44 upon the relatively opposite side of piston head 40, thus placing the cylinder space 42 in communication with the annular 110

channel or groove 27 and the cylinder space 44 in communication with the annular groove 28.

- The manual controlling and actuating rod 37 before referred to, is provided at its end opposite the angular extension 36, with a handle 45 and with a toothed rack 46 adjacent said handle, the latter working through a rigid bearing 47 having an inner tooth 48 adapted for engagement with the rack 46 at a selected point to lock the rod 37 in selected adjustment, the openings 49 of bearing 47 being sufficiently large to permit of lateral movement of the rod 37 to effect engagement thereof with, and disengagement thereof from, the tooth 48 of the bearings, and being provided with a spring 50 engaging the rod to normally hold the same in engagement with the said tooth 48.
- Thus, in operation, when it is desired to extend the reach rod 14 for actuating the parts to be controlled in one direction, as, for instance, in the present case, lowering the link hanger 13, the manual controlling rod 37 is disengaged and thrust longitudinally away from the operator, thus moving the piston valve to the right in Fig. 4, and uncovering the groove 27 to establish communication between the same and the outer end of the bore 21, and consequently in communication with the source of fluid pressure through the nipple 24 and the channel 38, at the same time uncovering the groove 28 to the atmosphere through the slot 18. The fluid pressure consequently finds its way through the port 29 and through tube 31 to the cylinder chamber 42 upon the left hand side of the piston 40 in Fig. 3, and accumulates to force the piston 40 to the right, thus moving the controlling member 15 which is rigid and movable with the piston and its rod 32, and thus effecting the desired outward longitudinal movement of the reach rod 14, it being understood that, during this operation, the operator holds the controlling rod 37 out of engagement with the tooth 48 of the bearing 47. When the desired extent of movement has been reached, the operator releases the handle 45 of the controlling rod 37, and the spring 50 immediately forces the rack 46 into engagement with the tooth 48, and during the further slight movement of the controlling member 15, the piston valve is moved to the left in Fig. 4 with respect to the said controlling member, by virtue of the slight relative movement of the angular end 36 of the controlling rod 37 in the slot 18. This movement causes the heads 33 and 34 to first lap the grooves 27 and 28 and then causes head 34 to uncover groove 28, and establish communication between the groove 28 and the source of fluid pressure through the nipple 24, groove 27 in the meantime remaining covered by virtue of the exhaust

lap of the valve. The pressure thus passes through port 30 and hollow piston rod 32 to the cylinder space 44 upon the right hand side of the piston 40, so that upon accumulation of pressure the head is moved to the left in Fig. 3, these parts subsequently arriving at and maintaining an equilibrium of pressure in the cylinder 39 until the controlling rod 37 is again released and moved longitudinally in one direction or the other.

It is obvious that, in addition to the foregoing operation, the parts are capable of manual control alone, by virtue of the fact that the controlling member 15 is movable, and the controlling rod 37 is capable of actuating the same to move the reach rod 14 in one direction or the other, the said rod 37 having only limited movement with respect to the controlling member 15.

It is also obvious that, due to the particular construction, the reversing gear or other mechanism to be controlled, is prevented from "creeping" beyond the exhaust lap of the controlling valve, including the heads 33 and 34.

It is obvious, furthermore, that in addition to the provision for manual control in case of failure of the fluid pressure supply, my invention provides an arrangement wherein leaky piston rings, valve rings, packing, or joints will have little if any effect upon the general operation so long as the supply of fluid is greater than the leakage, and obviates the necessity of maintaining the reversing gear in first class condition at all times.

I claim:

1. In a controlling mechanism of the character described, the combination with parts to be controlled, of a controlling member having connection with the parts to be controlled and having an upper transverse slot and axially aligned bores upon opposite sides of the said slot, each of said bores being provided in its wall with an annular groove, and one of said bores having communication at its outer end with a pressure supply nipple, the inner ends of said bores communicating with the atmosphere through the slot, said controlling member having a pair of ports therein, respectively communicating with said grooves, a power cylinder, a piston movable therein and connected to the said controlling member, means establishing communication between the said ports of said controlling member and the said power cylinder at opposite sides of the piston, a piston valve including spaced heads disposed within the said bores of the controlling member and normallylapping the said grooves of the bores, said controlling member having pressure channels communicating between the relatively opposite ends of its said bores beyond the said valve heads, and a manual controlling rod having one angular

lar end connected to the stem of the piston valve within the transverse upper slot of the controlling member.

2. In a controlling mechanism of the character described, the combination with the parts to be controlled, of a power cylinder having a pressure actuated piston, a source of fluid pressure connected to said cylinder, a controlling member connected to the piston of said cylinder and movable therewith and having a valve controlling the supply of fluid pressure to said cylinder, connections between said controlling member and the parts to be controlled, a manually actuated member having connection with said valve, said manually actuated member normally having a limited movement in respect to said controlling member and engageable with the latter at the limits of its movement, whereby the controlling member may be shifted by hand, and means for locking said manually actuated member in selected position.

3. In a controlling mechanism of the char-

acter described, the combination with the parts to be controlled, of a power cylinder having a pressure actuated piston, a source of fluid pressure connected to said cylinder, a controlling member connected to the piston of said cylinder and movable therewith, and having a slotted portion with piston chambers at opposite sides of the slot, a valve controlling the supply of fluid pressure to said cylinder, having pistons in said piston chambers and a portion connecting the said pistons and extending through the slot of the controlling member, connections between said controlling member and the parts to be controlled, a manually actuated member having connection with said valve at a point between its said pistons and within the slot of said controlling member, and means for locking said manually actuated member in adjusted position.

LEO IMBLUM.
